UNITED STATES PATENT OFFICE.

PHILIP JONES, OF SANTA MARIA, CALIFORNIA.

PROCESS OF PUMPING OIL-WELLS.

1,102,152.

Specification of Letters Patent. Patented June 30, 1914.

Application filed March 16, 1914. Serial No. 824,843.

To all whom it may concern:

Be it known that I, PHILIP JONES, a citizen of the United States, residing at Santa Maria, in the county of Santa Barbara, State 5 of California, have invented new and useful Improvements in Processes of Pumping Oil- Wells, of which the following is a specification.

This invention relates to improvements in 10 the method of pumping oil wells by what is now known as the air lift method; and the invention consists fundamentally in provision of means whereby the lighter hydro- carbons which are now carried in vaporous 15 form in the air may be separated and saved instead of being lost as is now the case.

The present practice in pumping oil wells by air lift is to force compressed air through 20 an air pipe to the bottom of a tubing or flow pipe in the well and to release the air in the tubing to form a column of mixed oil and air which is lighter than the column of oil standing outside the flow pipe. The column of mixed oil and air is raised and continuous 25 flow is caused by an unbalanced pressure of the column outside the flow pipe. The quantity of air depends entirely upon conditions under which the pump is operated; but in many cases the volume of air far exceeds the volume of oil pumped. This air, 30 being in intimate contact with the oil, takes up a great amount of lighter hydro-carbons, such as gasolene; and when the air escapes to the atmosphere these lighter hydro-carbons 35 evaporate and are lost. It is impracticable to separate the hydro-carbons from the air by compression and cooling, as the compression would generate sufficient heat to cause disastrous ignition of the hydro-car- 40 bons and air. I propose to eliminate these difficulties by substitution, for the air, of some gas which will not support combustion of the hydro-carbons, and by the provision of means (including compression) for sepa- 45 rating and saving the lighter hydro-carbons.

One aspect of my invention is that of pumping a well with a gaseous fluid and separating and saving the lighter hydro-carbons which are ordinarily lost.

50 Another aspect of my invention is the separation of mixed hydro-carbons into different fractions.

It will be seen from the following specification that, although I describe my invention as particularly applied to pumping oil

wells, yet my invention may be applied to the separation of lighter hydro-carbons from a mixture of hydro-carbons regardless of whether the mixed hydro-carbons are in a well or in a tank or the like.

60

I have illustrated in the accompanying drawings, a mechanism for carrying out the preferred form of my invention, the single view being a diagram of the various parts in section. In these drawings the numeral 65

10 may designate the casing of a well, 11 the flow pipe thereof, and 12 the pipe through which compressed gas is forced to the bottom of the flow pipe 11. The relative ar- 70

angement of the flow pipe and gas pipe is 75 of no consequence so far as my present invention is concerned, excepting that the gas pipe delivers the gas to the lower end of the flow pipe in such a manner that the column of oil inside the flow pipe is lightened while 80 the column outside the flow pipe remains unlightened. It is a fundamental feature of my invention that I use a gas which will not support combustion of the hydro-carbons; and natural gas complies with this condition 85

and is very plentiful in oil regions. I prefer to force natural gas under pressure through the gas pipe 12; and the mixed oil and gas will emerge through the top of the 90 flow pipe 11 into a separator tank 13. In 85 this separator tank there is little or no pres-

sure, due to the fact that the gas has ex- 95 panded as it rises through the flow pipe, and the work delivered by the compressor to the gas has been expended by the gas in rising through the flow pipe. The gas with the vapor of the lighter hydro-carbons will pass through a pipe 14 to the compressor 15 where the gas and vapors are compressed, and thence pass through a suitable condenser 16 and thence into a suitable separator 17. In 100 this separator the condensed vapors are sepa- 95 rated from the fixed gases, and the fixed gases pass again through the pipe 18 back to the pipe 12 which extends down into the well.

The gas in my system is used con- 105 tinuously in a closed cycle. New gas may be supplied through pipe 19 from time to time to make up for any loss or deficiency. The oil may be drawn off from the separator tank 13 and the lighter hydro-carbons from the separator tank 17, either continuously or intermittently as may best suit. The tem- 110

perature to which the gases and vapors are lowered in the condenser 16 will, of course,

depend upon the temperature necessary to condense the vapors and cause their separation from the fixed gases.

In its more specific aspect, my invention is for the purpose of pumping oil wells by means of the compressed fluid system without the loss of the lighter hydro-carbons. It is this aspect of my invention that I wish to particularly secure to myself in the following claims; it being understood that I do not limit myself specifically to the exact details of the method or mechanism herein set forth but only to the fundamental steps necessary for carrying on my invention as herein described.

I claim:

1. The herein described method of pumping oil wells, comprising the formation of a column of mixed oil and a gas incapable of supporting combustion, the separation of the oil and gas, and the separation of the gas and the vapors carried thereby by means including compression.
2. The herein described method of pumping oil wells, comprising the formation of a column of mixed oil and a gas incapable of

supporting combustion, the separation of the oil and gas, and the separation of the gas and the vapors carried thereby by means including compression and cooling.

3. The herein described method of pumping oil wells, comprising the formation of a column of mixed oil and natural gas in balance with a column of oil so that the mixed column is raised, the separation of the oil and gas and the separation of the gas and the vapors carried thereby.

4. The herein described method of pumping oil wells, comprising the formation of a column of mixed oil and natural gas in balance with a column of oil so that the mixed column is raised, the separation of the oil and gas and the separation of the gas and the vapors carried thereby by means including compression and cooling.

In witness that I claim the foregoing I have hereunto subscribed my name this 23d day of February 1914.

PHILIP JONES.
